CLAMP FOR MASTER SHEETS OF PRINTING MACHINES

Lawrence H. Morse, Mentor, Ohio, assignor to
Addressograph-Multigraph Corporation, Cleve-
land, Ohio, a corporation of Delaware

Application January 10, 1944, Serial No. 517,683

9 Claims. (Cl. 101—415.1)

This invention relates to a means for clamping a master sheet on a drum of a printing machine. One of the objects of the invention is to provide a clamping mechanism which may take a variety of master sheets, whether the same be metal or paper or other material, and whether they are provided with a row of openings across one end (as is frequently the case) or have the end portion imperforate.

In carrying out my invention, I provide clamps for the leading end and trailing end of the sheet, each of which has provision for securing a sheet by projections extending through openings therein or by distorting the sheet into a recess, resulting in kinking it, to effect a clamping action. The clamping action by means of the projections is well adapted for metal plates, or plates of other material having sufficient thickness of body to enable the sheet to be perforated without danger of tearing. On the other hand, the portions of the clamps which effect their holding action by kinking the sheets are especially adapted for thin sheets such as may be made of paper.

My invention is illustrated in a preferred form in the drawings and hereinafter described in detail. As there shown the clamp for the leading end of the sheet is substantially the same as that shown in my pending application No. 504,656, filed October 2, 1943. The clamp for the trailing end of the sheet, however, is peculiar to the present application, which provides a single clamping member so formed, and cooperating with such an anvil, that they may effectively hold a perforated sheet by means entering the perforations or an imperforate sheet by means pressing it into a recess in the anvil. This operation will be more apparent from the following detailed description of the mechanism shown in the drawings.

In the drawings, Fig. 1 is a side elevation, partly broken away, of a printing drum equipped with my master sheet clamps for holding the two ends of the master sheet; Fig. 2 is a cross section of the drum in a plane indicated by the line 2—2 on Fig. 1 and showing the clamps closed but without a master sheet on the drum; Fig. 3 is a fragmentary cross section similar to Fig. 2 but showing the clamps in the open position; Fig. 4 is a fragmentary cross section of the drum showing the clamps closed on a thin paper sheet retained by kinking action; Fig. 5 is a similar cross sectional view showing the clamps closed in retaining a sheet provided with a row of openings across each end; Fig. 6 is a fragmentary view of a portion of either end of such master sheet as clamped in Fig. 5.

In Figs. 1 to 5, 10 designates a suitable rotary drum having a segmental recess or gap 11 through its periphery. Adjacent one edge of the gap is a ledge adapted to form an anvil for the clamp to secure the leading edge of the sheet. As shown in the drawings, this ledge is provided by a flat bar 15 secured in a radial position to the drum and having an outwardly facing longitudinal recess 16.

The clamping member for the leading end of the master sheet comprises a member 20 having a cross bar 21 longitudinal of the drum, a central arm 23 pivoted on a shaft 24 mounted in the drum, and a pair of arms 25, 26 abutting such shaft. The cross bar 21 carries a longitudinal strip which is bent on itself to provide an inwardly extending flange 27 in position to coat with the groove 16. Two or more pins 28 carried by the bar 15 form suitable stops for the inner end of the sheet to be clamped on the drum. The bar on the clamp is perforated to allow the passage of such pins, so that the sheet may not be inadvertently passed over the tops of the pins. A spring 29 secured to the drum and to the arm 23 tend to maintain the flange 27 in coaction with the ledge 15 to deflect a very flexible sheet between them and effectively clamp it, as illustrated by the sheet designated B in Fig. 4.

I also secure to the cross bar 21 of this clamping yoke a face bar 30 having projecting pins or hooks 31 adapted to extend through openings in a master sheet.

The construction just described enables the mounting of the leading end of master sheets of various forms. If the sheet has a row of holes through it adjacent the end (as illustrated for example by the sheet A in Figs. 5 and 6) it may readily be hooked over the hooks 31. If the end portion of the sheet is imperforate, as is frequently the case with a paper sheet, it may be readily clamped by the flanged edge 27 which kinks the end portion of a sheet into the groove 16 as shown in Fig. 4.

To provide ready means to force the clamping member 20 backwardly away from the ledge 15, I mount in such clamping member a threaded sleeve 35 which carries a freely slideable rod 36 abutting the ledge 15. In a bifurcated head on the sleeve I pivot a cam arm 38. When the clamping means provided by the flange 27 and the ledge 15 is to be idle, the clamping arm 38 is positioned outwardly in alignment with the sleeve 35, as shown in Fig. 3. This draws the clamping member 20 outwardly so that the flange 27 is well away from the ledge 15 as shown in Fig. 3.

I will now describe the clamp for the trailing end of the master sheet, with which the present invention is particularly concerned. As shown in the various views, I have provided at the other edge of the gap in the clamp a stationary clamping ledge or anvil provided by a strip of material doubled on itself at an acute angle thus having a radial portion 40 secured to the radial face of the drum, and a portion 41 at an acute angle which extends in a direction of a chord into the gap and constitutes an anvil for the clamp.

The anvil 41 comprises an aligned row of fingers spaced by notches 42 corresponding in position to the openings in the master sheet to be clamped. Such a master sheet is indicated, for instance, at A in Fig. 6, where it is shown as having a scalloped end providing ears a with slotted openings a' through them. This is a form of master sheet which is in use, but the scalloping recesses between ears are idle in the operation of my clamp and the sheet could equally well be uninterrupted across the end except for the slots a', through which teeth on the clamp may extend.

As shown in each of the views, the clamping member for the trailing end comprises a cross plate 50 having its ends flanged inwardly at right angles to form arms 51. Each of these arms has a slot 52 embracing a projecting pin or a cross rod 53 on the drum. Secured to the free margin of the plate 50 is a sheet metal strip 55 bent inwardly at right angles and to provide a clamping edge 56 for the paper sheet, this edge being directly opposite aligned longitudinal grooves 48 in the anvil fingers. On the inner side of the strip 55 is a bar 57 having on its inner face a row of inwardly projecting teeth 58 which are located in registration with the notches 42 in the anvil. Tension springs 60 are secured to the clamping plate 50 at their outer ends, and at their inner ends are suitably anchored within the drum. As shown the inner ends are secured to collars 61 which for convenience embrace the rod 24 on which the leading-end-clamp is pivoted.

The intermediate portion of the plate 50 is cut away and material adjacent such cut-away portion is curled inwardly, as shown at 59, to provide suitable space for the operator's hand and a suitable edge for manual engagement to enable ready manipulation of the clamp.

When the trailing end of a perforated sheet is to be clamped, the clamp 50 is manually engaged by the operator's fingers at the edge 59 and pulled outwardly in an inclined direction which is partly radial and partly in a general direction toward the anvil, and then when the trailing end of the sheet has been inserted between the clamp and anvil the clamp is allowed to swing inwardly under its spring action and the teeth pass through the openings in the sheet and the spring brings the sheet and clamp into coaction with the anvil, as shown in Fig. 5.

When clamping a perforate sheet the inwardly turned edge 56 lies against the face of the sheet while the spring 60 pulls the clamp along the anvil to maintain tension on the sheet, the clamp in such position having the end of its slot 52 free from the rod 53, as shown in Fig. 5. This effectively holds the trailing end of the sheet and maintains the sheet in tension about the drum, which is very desirable with a metal sheet or one of considerable stiffness.

In clamping a paper sheet having no perforations indicated at B in Fig. 4, the leading end is clamped by engagement of the flange 21 in co-

action with the groove 46 of the anvil plate, as already described. Then when the sheet is wrapped around the drum and the clamp is in the open position shown in Fig. 3, the trailing end 5 is inserted between the anvil and clamp and the clamp allowed to swing inwardly about the rod 53 as a pivot (the ends of the slots now abutting the rod) and this brings the edge 56 into engagement with the sheet directly opposite the groove 46 and kinks the sheet into the groove, as shown in Fig. 4. In this position the teeth 58 may press the extreme edge of the sheet inwardly slightly into the anvil recesses but such action is idle.

15 It will be seen that the clamp described for the trailing end of the sheet, while being very simple in construction, is adapted for clamping imperforate or perforated sheets and sheets of paper or metal or other material and may be very quickly operated either to clamp the sheet or to release it.

15 It is sometimes desirable to skew the master sheet after it has been mounted on the drum to true up the image, in case it is not strictly 25 parallel with the side edges of the sheet, and to effect this I provide means to shift one of the clamps lengthwise of the drum. This is very conveniently effected by mounting in the leading clamp a rod which is threaded in the clamp and 30 abuts the ends of the drum. As shown in Fig. 1, the arm 25 of the clamp embraces the rod 70 slidably, while the arm 26 is threaded to coact with threads 71 on the rod, and thus a turning of the rod (as for instance manually by a knurled 35 collar 72 thereon) effects the desired shifting.

I claim:

1. The combination of a drum having an anvil within a gap in the drum, a clamping member pivotally and slidably mounted within the drum 40 having inwardly projecting teeth, said clamping member having an inwardly projecting edge beyond the teeth, the anvil having a longitudinal groove with which said edge may coact to kink a sheet into the groove, and spring means tending 45 to constrain the clamping member inwardly.

2. The combination of a drum having an anvil within the gap in the drum, said anvil having a row of openings in it, a clamping member pivotally and slidably mounted within the drum having 50 inwardly projecting teeth registering with the openings, said clamping member having an inwardly projecting edge beyond the teeth, the anvil having a longitudinal groove with which the edge may coact to kink a sheet into the groove and means to force the clamping member inwardly.

3. The combination of a drum having a gap, an anvil in the drum having a longitudinal recess, a clamp slidably and pivotally mounted in the drum, a spring action on the clamp tending to hold it in its inward swinging position and also at the inner end of its sliding movement, an inward projecting edge on the clamp adapted to coact with the groove when the clamp is at the inner end of the sliding movement and teeth on the clamp back of said edge and adapted to engage openings in the plate and hold the same under tension when the clamp is some distance from the end of its sliding movement.

70 4. The combination of a drum having a gap, an anvil therein having a longitudinal groove, a clamping plate having slotted end arms, pivots carried by the drum for said arms whereby the clamp may swing inwardly and outwardly and also slide along said pivot, spring means acting

diagonally on the clamp to swing it inwardly and slide its slotted arms along the pivot, inwardly projecting teeth on the clamp adapted to engage openings in the sheet and an edge on the clamp adapted to coact with the groove in the anvil.

5. The combination with a drum having a gap, a clamp mounted therein comprising a plate and inwardly flanged ends forming arms, slots through said arms, pivots carried by the drum extending through the slots, the plate being recessed between the arms, the edge of the plate being curled inwardly at the recess to provide a finger grip, spring means acting on the plate tending to constrain it inwardly and to maintain it with the end of the slots in engagement with the pivots, an inwardly projecting longitudinal edge on the plate, an anvil on the drum with which said edge may coact and inwardly projecting teeth on the clamp.

6. The combination with a drum having a gap, a clamp mounted therein comprising a plate and inwardly flanged ends forming arms, slots through said arms, pivots carried by the drum extending through the slots, an inwardly projecting longitudinal edge on the plate, an anvil on the drum having a longitudinal groove with which said edge may coact, inwardly projecting teeth on the clamp in a row behind the clamping edge, and a tension spring anchored at its outer end to the clamp and extending in an inclined direction with reference to the clamp inwardly of the pivotal axis of the clamp and attached to the drum beyond such axis.

7. The combination of a drum having a gap, 35

an anvil within the gap, a swinging clamping member in the drum having an inwardly facing clamping portion adapted to coact with the anvil, a row of teeth on the clamping member out of range of the inwardly facing clamping portion, and spring means acting on the clamping member to constrain it toward the anvil and inwardly across the face of the anvil.

8. The combination of a drum having a gap, 10 an anvil in the drum having a row of openings, outwardly facing aligned grooves in the anvil between the openings, a swinging clamping member in the drum having an inwardly facing clamping edge adapted to coact with the grooves and 15 having a row of inwardly facing teeth being adapted to enter said openings, said teeth being formed into hooks with their openings away from said clamping edge, and a spring means acting on the clamping member to constrain it toward 20 the anvil.

9. The combination of a drum having a gap, an 25 anvil in the drum having a longitudinal groove on its outer face, a clamping member pivotally and slidably mounted within the drum, an inwardly projecting edge on the clamp adapted to coact with the groove in the anvil to kink a sheet between them, and teeth on the inner face of the clamp between the clamping edge and the pivot of the clamp adapted to occupy 30 openings in a sheet, and spring means acting on the clamp in a direction to constrain it inwardly toward the anvil and inwardly across the face of the anvil.

LAWRENCE H. MORSE.
